UNITED STATES PATENT OFFICE.

LEON LOBEL, OF NEW YORK, N. Y., ASSIGNOR TO DR. LOBEL'S SPRING ARCH SUPPORT CO., INC., OF NEW YORK, N. Y., A CORPORATION OF NEW YORK.

ARCH SUPPORT.

Application filed March 10, 1922. Serial No. 542,533.

To all whom it may concern:

Be it known that I, LEON LOBEL, a citizen of the United States, and a resident of the city, county, and State of New York, have 5 invented a certain new and useful Improvement in Arch Supports, of which the following is a specification.

This invention relates to an improvement in devices used for supporting the arches 10 of the feet, and has for its object to provide a device which will be simple in construction, light in weight; which may be worn with comfort at all times and which will be of an elastic or resilient construction 15 so that it may be worn without inconvenience and absolute comfort and performs its cure without effort or pain on the part of the user.

A further object of this invention is to 20 provide a means for "building up" or constructing an arch support to suit the foot in connection with which it is to be used. It has been found very difficult to apply the ordinary form of arch support to feet 25 of varying forms and possessing different defects. An arch support made in accordance with my invention may be constructed to remedy all defects of the feet as may be required by individual users.

30 With these and other objects in view, I have devised the particular arrangement of parts hereinafter set forth and more particularly pointed out in the claim appended hereto.

35 Reference is to be had to the accompanying drawing forming a part hereof in which—

Figure 1 is a plan view of an arch support made in accordance with my invention; 40

Figure 2 is a side elevation of the same, parts being broken away to disclose construction;

Figure 3 is a sectional view on the line 45 3—3 of Figure 1 looking in the direction of the arrows, and

Figure 4 is a sectional view on the line 4—4 of Figure 1 looking in the direction of the arrows.

50 Throughout the various views, similar reference characters designate similar parts.

In the preferred embodiment of my invention as disclosed in the accompanying drawing 1 indicates the body portion or supporting structure of the arch support. This

consists of a strip of substantially flexible material such as leather of substantial thickness and is shaped to fit the foot. Its central portion is raised or upwardly arched as at 2 to form the arch supporting portion of the device. 60

At 3 is a spring which is placed directly below the arched portion 2 of the body 1, which spring is supported upon a plate 4. Through this arrangement a resilient supporting means for the arch of the foot is 65 provided.

Some persons tend to walk on one side of the foot and to remedy this defect the heel portion 5 of the arch support may be 70 built up or thickened on one side or the other. This is done by splitting the body portion 1 inwardly from the side of the support which is to be raised or thickened thus dividing the body portion 1 into the 75 two outer faces 6 and 7 between which an insert of a soft yielding cellular material is secured. For this purpose I have found soft sponge rubber particularly useful. This insert which is disclosed at 8 is pref- 80 erably made thicker at its outer edge than at its inner end so that the top face 6 of the support is substantially smooth and even and can in no way inconvenience the wearer. It will be understood that any portion of 85 the arch support can be built up in this manner to correct different defects in the feet.

One of the common defects of the human foot is displacement of the metatarsal bones. 90 To hold the same in proper position without causing inconvenience or pain, I provide the body portion 1 with a cushion 9 located adjacent the front end of the device and in position to properly act upon the foot. 95 This cushion is formed by padding the body portion 1 between its two outer faces 9 with material similar to that disclosed at 8. This insert, which is indicated at 11 may be placed in position by slitting the front edge 100 10 of the body portion, thereafter securing that edge by means of the line of stitches 12. This provides a cushion of extreme resiliency yet of sufficient firmness to hold the metatarsal bones effectively in position. The cushion 9 is entirely surrounded by portions of the body portion 1. The foregoing indicates two methods of building up portions of the support to correct 105 common defects of the foot. 110

It will be understood that my invention is not to be limited to the exact embodiment shown but is broad enough to cover all structures coming within the scope of 5 the annexed claim.

What I claim is:

An article of the class described comprising a supporting strip of flexible material of a single thickness, said strip being upwardly arched at a substantially central point, a spring below said upwardly arched portion for resiliently supporting the same, said strip being inwardly split from one of its sides at its rear end with a wedge-shaped section of a soft, cellular and yield-

ing material held between the split portions of the strip to elevate the heel portion of the strip at one side, said strip also being split inwardly at its front edge, and a rounded cushion member adjacent the front edge of said strip forming an upwardly extending resilient protuberance on the upper face of the strip, said cushion member being formed by the insertion of a soft yielding and cellular section of rubber between the split portions of the strip adjacent the front edge of the same. 20 25

Signed at the city, county, and State of New York this 8 day of March, 1922.

LEON LOBEL.
